UNITED STATES PATENT OFFICE.

WILLIAM T. FITZPATRICK, OF WATERLOO, IOWA.

DESIGN FOR A FOUNTAIN-PEN.

52,868.

Specification for Design.

Patented Jan. 14, 1919.

Application filed July 23, 1917. Serial No. 182,354. Term of patent 14 years.

To all whom it may concern:

Be it known that I, WILLIAM T. FITZPATRICK, a citizen of the United States, residing at Waterloo, in the county of Blackhawk and State of Iowa, have invented a new, original, and ornamental Design for Fountain-Pens, of which the following is a specification, reference being had to the accompanying drawing, forming part thereof.

Figure 1 is an elevation of a fountain-pen, showing my new design.

Copies of this patent may be obtained for five cents each, by addressing the "Commissioner of Patents, Washington, D. C."

Fig. 2 is an elevation of said fountain pen, taken at an angle of ninety degrees from said Fig. 1.

I claim:

The ornamental design for a fountain-pen, as shown.

Waterloo, Iowa, July 5, 1917.

WILLIAM T. FITZPATRICK.
